CLAIM

The ornamental design an air inlet assembly for fire pit, as shown and described.

DESCRIPTION

FIG. 1 is an upper perspective view of an air inlet assembly for fire pit positioned in a fire pit showing our new design. FIG. 2 is a top plan view thereof.

FIG. 3 is a cut away upper perspective view thereof; and, FIG. 4 is a front elevation view thereof taken along line 4-4 of FIG. 2, the rear elevation and side elevation views being the same.

The dashed lines shown in the drawings are for purposes of illustrating portions of the article that form no part of the claimed design.

1 Claim, 4 Drawing Sheets
